UNITED STATES PATENT OFFICE.

JOHN C. MOORE, OF CONNERSVILLE, INDIANA.

VALVE-OPERATING MECHANISM.

Application filed August 14, 1920. Serial No. 403,490.

It is the object of my invention to provide a rocker-arm mechanism for operating the valves of internal combustion engines, whereby the valve starts its opening movement and finishes its closing movement relatively slowly but moves much more rapidly as the opening movement continues and during the first part of the closing movement; whereby a wide valve-opening is quickly obtained, and yet pounding of the valve on its seat is prevented, the effect of differential expansion between cylinder and push rod, requiring undue clearances to avoid opening of the valves when the engine is cold, is minimized, and a relatively large mechanical advantage is obtained for starting the valve movement, which is of special advantage for the exhaust valve because of the gas pressure against which it operates. This makes for greatly increased power in engine operation.

In accomplishing this result, I provide a rocker arm which has a rolling movement on its pivot and on the push rod and valve stem, whereby the push rod and valve stem may move in substantially straight lines and the pivotal point and the points of contact of the rocker arm with its three associated members are shifted in the rocking operation so that in the valve-opening movement the power arm of the lever is shortened and the work arm thereof is lengthened materially; and I provide the co-operating surfaces of the rocker arm and its pivotal surface and the push rod with co-operating pins and depressions which prevent the parts from relative slippage but do not interfere with the rocking movement.

The accompanying drawings illustrate my invention: Fig. 1 is a fragmentary view, partly in section, of a rocker arm mechanism embodying my invention, with the valve open; and Fig. 2 is a similar view with the valve closed.

The valve 10 is fixed on a slidable valve stem 11 to co-operate with the valve seat 12 in the usual manner, the usual springs 13 being provided for closing it. A push rod 15 is mounted for vertical reciprocation by the usual cam 16 on the cam shaft 17. These parts may be of any desired construction.

The push rod 15 acts on the valve stem 11 through a rocker arm 20. This rocker arm has a convex curved surface 21 on the under face of its work arm, to co-operate with the

plane upper end of the valve stem 11. It has a convex curved surface 22 on the under face of its power arm, to co-operate with the plane upper end of the push rod 15. The upper side of the rocker arm 20 has a pocket 23, the bottom of which is a convex surface 24 which bears against the plane lower face of a fulcrum screw vertically adjustable in a suitable support 26 and held in adjusted position by a lock-nut 27. The surfaces 21, 22, and 24 are all convex cylindrical surfaces, which roll on the respective plane surfaces formed by the stem, rod, and screw ends with which they co-operate, the surfaces 21 and 22 being convex downward and the surface 24 convex upward.

Thus as the rocker arm rocks from the position shown in Fig. 2 to the position shown in Fig. 1, to open the valve 10, the points *a* and *c* at which the surfaces 21 and 22 engage their co-operating plane surfaces shift to the left (to *a'* and *c'* respectively), while the point *b* at which the surface 24 engages its co-operating plane surface shifts to the right (to *b'*), thus shortening the power arm from *bc* to *b'c'* and lengthening the work arm from *ab* to *a'b'*. Thus the shifting of all three points *a*, *b*, and *c* co-operate in varying the leverage ratio, to increase the throw of the valve stem 11 as the opening movement of the valve 10 progresses. The reverse takes place on the closing movement of the valve, during which closing movement the valve starts rapidly but ends slowly, because of such reverse change in leverage ratio. This gives the push rod 15 a relatively large mechanical advantage in starting the valve 10 from its seat, minimizes the effect of differential expansion between push rod and cylinder, produces a quick and wide opening of the valve, and lets the valve strike its seat at the end of the closing movement relatively slowly and without pounding; and it is found in practice that it gives a marked increase in engine power.

In order to obtain this relatively great change in leverage ratio, from

$$\frac{bc}{ab} \text{ to } \frac{b'c'}{a'b'}$$

the curvature of the surfaces 21, 24, and 22 is made relatively slight, and such surfaces are arranged to give substantially a true rolling motion on their respective associated plane surfaces.

In order to prevent relative slipping between the rocker arm and its associated parts, the upper end of the valve rod 15 and the lower end of the fulcrum screw 25 are provided with axially extending holes 30 and 31 respectively, which may be simple cylindrical holes; and pins 32 and 33 with projecting heads are mounted in the rocker arm 20 to project into such holes respectively. The heads of the pins 32 and 33 are preferably circular in cross-section, and are curved axially, something like a gear tooth addendum, being larger at their bases where they abut against the rocker arm than at any other point. These pins co-operate with the holes 30 and 31 as the rocker arm 20 rocks, to hold such rocker arm in a definite position with relation to the fulcrum screw 25 and the push rod 15 so far as any slipping movements are concerned. By shaping the heads of the pins 32 and 33 as stated, they effectively prevent slippage of the rocker arm without interfering with the rolling co-operation thereof with its associated parts.

In addition, to hold the rocker arm 20 in proper transverse position on the valve stem 11, two washers 34 which overlap the upper end of such stem may be fastened to the sides of the associated end of the rocker arm by a transverse rivet 35, the nearer of such washers being removed (and the rivet being shown in section) to show more clearly the cooperation of the surface 21 with the end of the valve stem 11.

I claim as my invention:—

1. A valve-operating mechanism for internal combustion engines, comprising, in combination with the valve stem and a push rod, a rocker arm the ends of which engage the valve stem and the push rod, and a fulcrum which an intermediate point of the rocker arm engages, each of the three pairs of engaging surfaces being arranged to rock on each other and shift the points of inter-engagement, said fulcrum and said push rod being provided with holes in their ends, and pins carried by said rocker arm and having heads projecting into said holes.

2. A valve-operating mechanism for internal combustion engines, comprising, in combination with the valve stem and a push rod, a rocker arm the ends of which engage the valve stem and the push rod, and a fulcrum which an intermediate point of the rocker arm engages, each of the three pairs of engaging surfaces being arranged to rock on each other and shift the points of inter-engagement, said fulcrum and said push rod being provided with holes in their ends, and pins carried by said rocker arm and having heads projecting into said holes, the heads

of said pins being convexly curved axially so that they act as gear teeth in combination with said holes to prevent slippage without interfering with the rocking movement. 65

3. A valve-operating mechanism for internal combustion engines, comprising a fulcrum, a rocker arm having at an intermediate point a rocking mounting on the under face of said fulcrum, a push rod and a valve stem upon the upper ends of which the end portions of said rocker arm have rocker mountings respectively, said rocker mounting being arranged so that as either end of the rocker arm is moved upwardly its 70 point of contact with the part co-operating with that end is shifted toward the fulcrum and the point of contact of the rocker arm with the fulcrum is shifted toward the end moving upwardly, said rocker arm and said 75 fulcrum being provided one with a hole and the other with a pin projecting into the hole, the projecting part of said pin being convexly curved axially so that it does not interfere with the rocking movement of the 80 rocker arm and in all positions holds it from slipping on the fulcrum.

4. A valve-operating mechanism for internal combustion engines, comprising, in combination with the valve stem and a push 90 rod, a rocker arm the ends of which engage the valve stem and the push rod, and a fulcrum which an intermediate part of the rocker arm engages, said rocker arm being provided at one end with a convex surface 95 which rolls on the end of said push rod when the rocker arm is rocked, and said convex surface being provided with a projecting longitudinally curved tooth and said push rod with a hole into which said tooth projects. 100

5. A valve-operating mechanism for internal combustion engines, comprising, in combination with the valve stem and a push rod, a rocker arm the ends of which engage 105 the valve stem and the push rod, and a fulcrum which an intermediate part of the rocker arm engages, said rocker arm being provided at one end and at such fulcrum with convex surfaces which roll on the end 110 of said push rod and on said fulcrum respectively when the rocker arm is rocked, and said convex surfaces being provided with projecting longitudinally curved teeth and said push rod and said fulcrum with 115 holes into which said respective teeth project.

In witness whereof, I have hereunto set my hand at Connersville, Indiana, this 11th day of August, A. D. one thousand nine hundred and twenty.

JOHN C. MOORE.
